UNITED STATES PATENT OFFICE

ADRIAN C. VAN HOOYDONK, OF BUFFALO, NEW YORK, ASSIGNOR TO JOHN E. SMITH'S SONS COMPANY, OF BUFFALO, NEW YORK, A CORPORATION OF NEW YORK

SAUSAGE STUFFER

Application filed July 26, 1928. Serial No. 295,468.

This invention relates to improvements in sausage stuffers of the type embodying a cylinder having a cover carried by a laterally-swinging yoke, and a free piston or plunger operable in the cylinder by compressed air or other fluid under pressure.

One of its objects is to provide simple and reliable means for insuring a tight joint and safety seal between the cover and the cylinder.

Another object of the invention is the provision of effective and inexpensive means for clamping the cover-yoke in place, such means being arranged to render the top of the cylinder free and unobstructed when the cover is opened to load the device.

In the accompanying drawing:—Figure 1 is a sectional elevation of a sausage stuffer constructed in accordance with my invention. Figure 2 is an enlarged horizontal section, taken substantially in the plane of line 2—2, Figure 1. Figure 3 is an enlarged vertical section taken on line 3—3, Figure 2.

Similar characters of reference indicate corresponding parts throughout the several views.

In the stuffer shown in the drawing, 10 indicates the upright cylinder for receiving the meat-dough or other plastic material and 11 the piston operable in the cylinder for ejecting the meat-dough therefrom through the customary spouts or nozzles 12. The lower end of the cylinder is closed and leading thereto is a pipe 13 for admitting the motive fluid under pressure to the cylinder for raising the piston.

Applied to the open upper or delivery end of the cylinder, and securely fastened thereto by cap screws or otherwise, is a safety-ring 14 which projects inwardly a suitable distance beyond the inner wall of the cylinder to form a stop or shoulder which prevents blowing out of the piston 11 should the operator neglect to turn off the motive fluid before opening or removing the usual cover 15 normally serving to seal the open end of the cylinder. This cover is applied to the lower end of an upright clamping screw 16 provided at its upper end with a handle

55 swinging yoke 18 fulcrumed at one side to a pivot bolt 19 rising from a lug or boss 20 projecting laterally from the upper end of the cylinder 10. Intermediate its upper and lower ends this pivot bolt has a flange or collar 21 which engages a corresponding opening 22 in an ear 23 of the safety-ring 14 and bears at its lower side against the opposing top side of the cylinder-lug 20. By this construction, the safety-ring, upon removing its fastening screws, can be swung to one side when desired without wholly detaching it from the cylinder.

60 The free end of the cover-carrying yoke 18 is detachably locked to the cylinder for firmly holding it against vertical or lateral displacement by means which preferably consist of bolts 24 and 25 secured, respectively, to the yoke and a boss 26 projecting from that side of the cylinder diametrically opposite the pivot-bolt 19 of the said yoke. In the normal closed position of the yoke shown by full lines in Figure 1, these bolts are in vertical alignment and their opposing ends terminate in heads 27, 28 which are shaped 65 to slidably interlock with each other as the cover-yoke is swung to its operative position. For this purpose, each bolt-head is substantially hook or L-shaped in cross section, the horizontal portion of one overlying 70 that of the other, as clearly shown in Figure 3, and being provided in their contiguous faces with companion tongues and grooves 29 and 30, respectively, which interlock with one another to reliably hold the yoke against 75 vertical displacement. These tongues and grooves are shaped circumferentially relatively to the pivot 19 of the yoke, as shown in Figure 2, so that as the latter is swung laterally over the cylinder, these parts will 80 properly register. In order to center the yoke in its operative position over the yoke and prevent its lateral displacement, a locating device, preferably in the form of a ball 31 is provided. This ball is arranged in 85 an opening in the head of the bolt 25 and is backed by a coil spring 32 for urging it into a corresponding seat or depression 33 in the opposing side of the head of the bolt 24.

90 95 100 The cover 15 is adapted, in its sealed or

closed position, to seat itself into the opening in the safety-ring 14. I provide a double safety seal for this purpose and to this end the opening in the safety-ring has upper and lower conical or beveled seats 34, 35, respectively, the lower seat converging downwardly and inwardly at a slight angle, say about nine degrees, and the upper seat converging in the same direction at about a forty-five degree angle, as shown in Figure 3. The periphery of the cover is provided with corresponding beveled joint edges 36, 37 cooperating with the companion ring seats. The lower joint edge 37 of the cover 15 contains an annular groove 38 in which is seated a rubber packing 39 arranged to engage the companion seat 35 of the safety-ring to insure a tight joint between the latter and the cover. As the clamping screw 20 16 is turned to seat the cover, the packing 39 is first pressed into sealing engagement with the ring 14 after which the upper joint edge of the cover is brought into engagement with the companion ring-seat 34, thereby acting as a safety seal and effectually 25 guarding against blowing out of the cover under the high pressure existing in the cylinder 10 of the stuffer.

I claim as my invention:—

1. A sausage stuffer, comprising a cylinder open at its upper end, a piston operable therein, a cover for the cylinder, a laterally-swinging yoke carrying said cover and fulcrumed at one side of said cylinder, and headed fastening devices detachably applied to the opposite side of said cylinder and to the adjoining end of said yoke in opposing relation for sliding and interlocking engagement with each other.

2. A sausage stuffer, comprising a cylinder open at its upper end, a piston operable therein, a cover for the cylinder, a laterally-swinging yoke fulcrumed at one side of said cylinder and carrying said cover, and complementary interlocking devices rising from the opposite side of said cylinder and depending from the adjoining end of said yoke and including attaching shanks and heads, the latter being shaped to form oppositely 50 facing hook-shaped elements arranged for sliding engagement with each other.

3. A sausage stuffer, comprising a cylinder open at its upper end, a piston operable therein, a cover for the cylinder, a laterally-swinging yoke fulcrumed at the upper end of said cylinder at one side thereof and carrying said cover, the free end of said yoke terminating above the top of the cylinder, and complementary detachable interlocking 60 devices rising from said cylinder and depending from the free end of said yoke and including attaching shanks and heads, the latter having oppositely facing hook-shaped elements arranged for sliding engagement 65 with each other, said hook-shaped elements

being circumferentially disposed in a horizontal plane relative to the fulcrum of the yoke.

4. A sausage stuffer, comprising a cylinder open at its upper end, a piston operable therein, a cover for the cylinder, a laterally-swinging yoke fulcrumed at the upper end of said cylinder at one side thereof and carrying said cover, and headed fastening devices detachably applied to the diametrically opposite side of said cylinder and to the free end of said yoke, the heads of said devices including interlocking tongues and grooves arranged to register with one another in the closed position of the cover-carrying yoke. 70

5. A sausage stuffer, comprising a cylinder open at its upper end, a piston operable therein, a cover for the cylinder, a laterally-swinging yoke fulcrumed at the upper end of said cylinder at one side thereof and carrying said cover, headed fastening devices detachably applied to the diametrically opposite side of said cylinder and to the free end of said yoke, respectively, the heads of said devices including interlocking tongues and grooves arranged to slidably engage one another in the closed position of the cover-carrying yoke, and a locating element carried by one of said fastening devices for interlocking engagement with the companion 80 fastening device. 85

6. A sausage stuffer, comprising a cylinder open at its upper end, a piston operable therein, a safety-ring applied to the open end of said cylinder and having upper and lower downwardly-converging seats extending around its inner edge, a cover movable into and out of engagement with the seats of said safety-ring and having its periphery provided with companion upper and lower downwardly-converging seats, a packing applied to one of said cover-seats, a laterally-swinging yoke fulcrumed at the upper end of said cylinder at one side thereof and carrying said cover, and complementary detachable 100 interlocking devices rising from the opposite side of said cylinder and depending from the free end of said yoke and including oppositely facing hook-shaped elements arranged for sliding engagement with each other. 105

7. A sausage stuffer, comprising a cylinder open at its upper end, a piston operable therein, a safety-ring applied to the open end of said cylinder and having upper and lower downwardly-converging seats extending around its inner edge in adjoining relation, a cover having its periphery provided with companion adjoining upper and lower downwardly-converging seats, a carrier for said cover including means for urging the cover into and out of engagement with said safety-ring seats, and a packing ring applied to the lower cover-seat for engagement 110 with the companion lower safety-ring seat, 115 120

the upper cover-seat being in sealing engagement with its companion safety-ring seat when the packing ring is compressed in sealing engagement with its companion safety-ring seat.

- 8. A sausage stuffer, comprising a cylinder open at its upper end, a piston operable therein, a safety-ring applied to the open end of said cylinder and having upper and lower downwardly-converging seats extending around its inner edge in adjoining relation, a cover having its periphery provided with companion adjoining upper and lower downwardly-converging seats, a laterally-swinging yoke carrying said cover and including means for urging the cover toward said safety-ring seats, and a packing ring applied to the lower cover-seat for engagement with the companion lower safety-ring seat, the upper cover-seat being in sealing engagement with its companion safety-ring seat when the packing ring is compressed in sealing engagement with its companion safety-ring seat.
